UNITED STATES PATENT OFFICE.

CLARK NOBLE WISNER, OF MEMPHIS, TENNESSEE.

COTTON-PICKER.

1,182,518.

Specification of Letters Patent. Patented May 9, 1916.

Application filed September 20, 1915. Serial No. 51,681.

To all whom it may concern:

Be it known that I, CLARK N. WISNER, a citizen of the United States, and a resident of Memphis, in the county of Shelby and State of Tennessee, have invented certain new and useful Improvements in Cotton-Pickers; and I do hereby declare the following to be a full, clear, and exact description of the invention, such as will enable others skilled in the art to which it appertains to make and use the same.

This invention relates to improvements in cotton pickers,—one object of the invention being to provide simple and efficient means which will facilitate the picking of cotton from individual bolls and which will insure the removal of all the cotton and cotton seed contained in the boll and exclude all foreign substances, such as leaves, sticks, etc.

20 A further object is to so construct a cotton picker that it may be easily and conveniently handled by the operator and enable him to readily reach the bolls on all parts of growing plants, without necessity 25 of bending his body to unnatural and uncomfortable positions, and to thus simplify and decrease the labor of cotton picking.

With these and other objects in view, the invention consists in certain novel features 30 of construction and combinations of parts as hereinafter set forth and pointed out in the claims.

In the accompanying drawings; Figures 1 and 2 are transverse sectional views of a 35 picker head embodying my improvements, and showing, respectively, different positions assumed by the picker pins or fingers during the operation of the device; Fig. 3 is a longitudinal sectional view, partly in elevation, and Fig. 4 is a transverse sectional view illustrating a modification.

The frame of the picker head comprises two end plates 1, 2, spaced apart and connected by bars 3, 3. The end plates are made 45 with openings 4 in which a suction tube 5 is fitted, said suction tube extending beyond one end of the frame for connection with suitable suction apparatus and a receptacle (not shown) and the portion of the suction 50 tube extending rearwardly from the end plate acting as a handle for the picker head. The suction tube is made with an opening 6 which extends approximately from one end plate to the other to receive cotton from the 55 picking devices.

In constructing the picking devices, I employ two shafts 7, 7, carrying picker pins 8, 9, projecting in opposite directions from each of said shafts,—the pins 8 being rigidly secured to the shafts and the pins 9 being 60 carried by collars 10 mounted loosely on said shafts. One of the shafts 7 carries a greater number of pins than the other and the pins of one shaft intermesh with those of the other shaft as shown in Figs. 1 and 3, 65 during the picking operation.

A tube 11 surrounds each shaft 7, in a manner to be capable of movement laterally at right angles to the axis of the shaft, said tube being made with perforations through 70 which the picker pins 8, 9, pass freely, so that when the shafts 7 are rotated, the tubes 11 will also be rotated. Any desired number of fixed pins 8 may be employed to insure proper rotation of the tubes when the shafts 75 are rotated, and by mounting some of the picker pins (as the pins 9) loosely on the shaft, so that they may pass freely through the holes in the tubes without appreciable pressure against the walls of the holes, the 80 friction between the pins and tubes will be reduced. Each tube 11 of the picker devices is provided in its respective heads with elongated slots 12 to receive pins 13 (having rollers 14 thereon) secured to the end plates 85 of the frame, so that when the shafts 7 and tubes 11 are rotated (in opposite directions) lateral motion at right angles to the axes of the shafts, will be imparted to the tubes 11 and cause said tubes to move over the inwardly projecting pins and strip the cotton 90 from the same during the movement of said inwardly projecting pins from the positions shown in Fig. 1 past the positions shown in Fig. 2,—during which movement of the 95 pins, over the opening 6 of the suction tube, the picked cotton will be deposited into the latter.

Instead of the roller-and-pin construction shown in Figs. 1 and 2 for stripping the 100 cotton from the picker pins, I may employ cams 15 carried by plates 16 secured to end plates of the picker head and operating in elongated slots in the ends of the tubes 11 as shown in Fig. 4.

105 During the rotation of the picker devices and when the tubes move inwardly to expose the outwardly projecting picker pins, the latter will pass between guard fingers 17 secured to the connecting bars 3 110.

of the picker head and projecting over the tubes 11 in a manner to prevent the entrance of trash, leaves, etc., into the picker head.

- The outer ends of the shafts 7, 7, project 5 beyond their bearings in the end plate 2 of the head, for the reception of the intermeshing gears 18, 19,—said gears being disposed within a housing 20 secured to the end plate 2. A flexible shaft 21 is coupled with one 10 of the shafts 7 as shown in Fig. 3 and receives motion from any suitable source of power. By thus gearing the shafts 7 together and applying motion to one of them, the picking devices will be operated to effectually pick the cotton from the bolls and deposit the same into the suction tube, without danger of clogging the picker head or permitting the passage of trash, etc., to the suction tube.
- 20 Various slight changes might be made in the details of construction of my invention without departing from the spirit thereof or limiting its scope and hence I do not wish to restrict myself to the precise details herein 25 set forth.

Having fully described my invention what I claim as new and desire to secure by Letters-Patent, is:—

1. In a picker head, the combination with 30 a frame, two shafts mounted therein, and picker pins carried by said shafts, of laterally and revolubly movable tubes surrounding said shafts, each tube being perforated for the passage of the picker pins 35 and each having elongated slots in its heads, and means projecting inwardly from the ends of the frame and entering said elongated slots to cause the tubes to move parallel to a plane at right angles to the axes of the shafts when said tubes are rotated by 40 engagement of the picker pins therewith.

2. In a picker head, the combination of a frame comprising two end plates spaced apart and each having an opening therein, 45 a suction tube mounted in the openings in the end plates and having an elongated opening between said end plates, shafts mounted in the end plates, picker pins carried by said shafts, laterally and revolubly 50 movable tubes surrounding said shafts and having perforations for the passage of the picker pins, means for rotating said shafts, and means for moving the tubes at right

angles to the axes of the shafts for stripping the picker pins.

55

3. In a picker head, the combination with a frame, shafts mounted therein, and means for rotating said shafts, of picker pins rigid with said shafts, picker pins loosely mounted on said shafts, tubes surrounding said shafts and having perforations for the passage of all of said picker pins, and means for moving said tubes parallel to a plane at right angles to the axes of the shafts when the latter and the picker pins are rotated.

4. In a picker head, the combination of a frame comprising end plates and bars connecting said end plates, shafts mounted in the end plates, means for rotating said 70 shafts, picker pins carried by said shafts, laterally and revolubly movable tubes loosely surrounding said shafts and having perforations for the free passage of the picker pins, means for moving said tubes in 75 directions at right angles to the axes of the shafts, and guard fingers secured to the connecting bars of the frame and projecting between the picker pins and over said tubes.

5. In a picker head, the combination of a 80 frame comprising two end plates spaced apart and each having an opening therein, a suction tube handle mounted in the openings in the end plates, the suction tube handle extending rearwardly from the picker 85 head and adapted to serve as a conveyer for cotton and cotton seed to a given point, shafts mounted in the end plates, picker pins carried by said shafts, laterally and revolubly movable tubes disposed between 90 the end plates and having elongated slots in their ends, surrounding said shafts and having perforations for the passage of the picker pins, means for transmitting motion to said shafts, and means coöperating with 95 the slotted ends of said tubes for moving the tubes parallel to a plane at right angles to the axes of the shafts for stripping the picker pins.

In testimony whereof, I have signed this 100 specification in the presence of two subscribing witnesses.

CLARK NOBLE WISNER.
